WRITING IMPLEMENT OR THE LIKE

Clarence Zierhut, Los Angeles, Calif., assignor to Paper Mate Manufacturing Company, Culver City, Calif., a corporation of Delaware

Application February 1, 1957, Serial No. 44,718

Term of patent 14 years

(Cl. D74—17)

FIG. 1.

FIG. 2.

FIG. 3.

Fig. 1 is a front elevational view of a writing implement, showing my new design;

Fig. 2 is a side elevational view thereof; and

Fig. 3 is a rear elevational view thereof.

The essential features of my new design reside in the portions shown in solid lines in the drawing, the characteristic feature being the provision of polka dots in a regular pattern, such dots being of a color contrasting with the color of the barrel.

I claim:

The ornamental design for a writing implement or the like, substantially as shown and described.
